UNITED STATES PATENT OFFICE.

GUSTAV MÜLLER-NAEGELI, OF WADENSWIL, SWITZERLAND, ASSIGNOR TO THE FIRM
OF OEL & FARBFILM A.-G., OF WADENSWIL, SWITZERLAND.

PROCESS OF MANUFACTURING PELLICLES OF OIL AND OIL-PAINT.

1,175,169.

Specification of Letters Patent.

Patented Mar. 14, 1916.

No Drawing.

Application filed August 21, 1914. Serial No. 857,910.

To all whom it may concern:

Be it known that I, GUSTAV MÜLLER-NAEGELI, a citizen of the Republic of Switzerland, residing at Wadenswil, Switzerland, have invented new and useful Improvements in Processes of Manufacturing Pellicles of Oil and Oil-Paint; and I do hereby declare the following to be a full, clear, and exact description of the invention, such as will enable others skilled in the art to which it appertains to make and use the same.

According to a known process of manufacturing metallic pellicles and pellicles of paint a soluble agglutinant is applied to a suitable base material, for instance cloth or paper, there being then spread over said agglutinant a layer of metal or paint. Upon moistening the reverse of the paper or cloth the agglutinant may be again dissolved, so that the pellicle can be separated easily from the base. This known process has, however, the drawback that the pellicles produced are of a small size and that the manufacturing on a large scale is irrational owing to the intricacy of the process.

This invention relates now to an improved process, which is in many regards much more advantageous than the hereinbefore mentioned process and is so simple as to permit manufacturing such pellicles on a large scale.

The new process consists in impregnating the one side of a base material with an alkaline solution having the desired degree of strength and in preferably soaking the reverse of said base in oil-varnish. To said alkaline layer there is then applied a layer of oil or oil paint. The action of the oxygen of the air dries this layer of oil or oil paint, so that there is produced a pellicle. The alkaline layer on the under side of the layer of oil or oil paint has the effect to saponify, owing to its caustic action, the under side of the pellicle of paint, thus preventing the latter from sticking to the base material and permitting separation of the pellicle from the base material.

In carrying the improved process into effect I may proceed, for instance, as follows: A strip of strong weakly sized and very absorbent paper, for instance paper used for producing patterns, having a suitable length and width is spread upon a smooth surface and its upper side is impregnated with water-glass having the nec-

essary degree of strength. Then said strip of paper is taken off said surface and its reverse is soaked in oil-varnish. This has the effect of preventing the strip of paper from absorbing any moisture upon a subsequent renewal of the layer of water-glass so that it will retain its smooth surface. The paper, which has been impregnated in the hereinbefore described manner, is then fixed by means of rails to a bottom of suitable length and width. The layer of water-glass comes thereby to lie upward. Over this layer there is now spread a layer of oil-varnish or oil paint, which according to circumstances may be made very thin or which may have a suitable thickness. If desired, I may add to said oil-varnish or oil paint a siccative liquid, rubber or the like. After 5-10 hours there will be found on the surface of the water-glass a pellicle of oil or oil paint having a non-adhesive surface, which, owing to the caustic action of the alkaline layer producing a saponification, is prevented from sticking to the base material, so that it may be separated without using any special means in strips of any desired length and width, provided that the saponification has not become ineffective through too long waiting. The chemical process of the saponification renders the under side of the pellicle of oil or paint adhesive. The adhesive power of this pellicle is, however, not sufficient to connect the pellicle of paint to the base material while the alkaline layer exerts a caustic action. This caustic action lasts, however, a great length of time, so that there can be produced several pellicles of paint without the alkaline layer having to be renewed. On the other hand, the adhesive power of the under side of the pellicles produced according to my improved process makes it possible to unite the separated pellicles to a suitable bottom material by simply pressing them against this bottom, so that no special adhesive substances of any kind have to be employed.

According to the alkaline degree of strength of the water-glass there can be obtained a weaker or stronger saponification on the back of the pellicles of paint. This permits varying accordingly the adhesive power of said pellicles.

The pellicles of oil and oil paint can be separated from the same base material in

- strips having a length of 10 to 100 meters and a width of 2 to 3 meters without applying and redissolving an intermediate layer. The pellicles of oil and oil paint produced according to the improved process forming the subject matter of my invention form a very valuable surrogate for the expensive caoutchouc. Owing to their great advantages they can be employed for very different purposes. Thus, they may be used on a large scale in the textile- paper- and wallpaper-industry, for instance for producing dust- and water-proof bags and every kind of packing materials. Further, they may be attached to woven goods of jute, linen and cotton; they may also be used as washable coverings for walls, as a building material in combination with slate-like materials such as "eternite", or wood, iron and the like. Said pellicles can also be employed for sanitary purposes and as clothing material, for instance for making aprons, bindings, bed-sheets and the like.

What I wish to claim is:

1. The process of manufacturing pellicles of oil and oil paint consisting in impregnating one side of a base material with an alkaline solution having the necessary degree of strength, applying to said alkaline layer a layer of oil varnish or oil paint respectively, drying this layer and finally separating the thereby produced pellicle of oil or oil paint respectively, said pellicle being prevented from adhering to the base material owing to the caustic action of the alkaline layer causing a saponification of the under side of the paint pellicle substantially as herein described.
2. The process of manufacturing pellicles of oil and oil paint consisting in impregnating the one side of a base material with an alkaline solution having the necessary degree of strength, soaking the other side of said base material in oil varnish, applying to said alkaline layer a layer of oil varnish or oil paint respectively, drying this layer and finally separating the thereby produced pellicle of oil or oil paint respectively, said pellicle being prevented from adhering to the base material, owing to the caustic action of the alkaline layer causing a saponification of the under side of the paint pellicle, substantially as herein described.
3. The process of manufacturing pellicles of oil and oil paint, consisting in impregnating the one side of a base material with water-glass having the necessary degree of strength, soaking the other side of said base

material in oil varnish or oil paint respectively, drying this layer and finally separating the thereby produced pellicle of oil or oil paint respectively, said pellicle being prevented from adhering to the base material, owing to the caustic action of the water-glass causing a saponification of the under side of the paint pellicle, substantially as herein described.

4. The process of manufacturing pellicles of oil and oil paint consisting in impregnating the one side of a base material with an alkaline solution having the necessary degree of strength, soaking the other side of said base material in oil varnish, applying to said alkaline layer a layer of oil varnish or oil paint respectively, drying this layer, separating the thereby produced pellicle of oil or oil paint respectively, said pellicle being prevented from adhering to the base material, owing to the caustic action of the water-glass causing a saponification of the under side of the paint pellicle, and in finally uniting the separated paint pellicle, whose reverse has become sticky owing to the saponification, without using any further adhesive material to a suitable bottom material, substantially as herein described.

5. The process of manufacturing pellicles of oil and oil paint consisting in impregnating the one side of a strong, weakly sized and strongly absorbent paper with an alkaline solution having the necessary degree of strength, soaking the other side of said paper in oil varnish, applying to said alkaline layer a layer of oil varnish or oil paint respectively, drying this layer and finally separating the thereby produced pellicle of oil or oil paint respectively, said pellicle being prevented from adhering to the paper, owing to the caustic action of the alkaline layer causing a saponification of the under side of the paint pellicle, substantially as herein described.

6. The process of making oil pellicles, which comprises applying water glass to a surface, painting said surface with oil paint or oil varnish, and stripping the film of paint or varnish, when dry, from the surface.

In testimony that I claim the foregoing as my invention, I have signed my name in presence of two subscribing witnesses.

GUSTAV MÜLLER-NAEGELI.
